(57) **CLAIM**

The ornamental design for a multi-segmented corridor light, as shown and described.

DESCRIPTION

FIG. 1 is a front perspective view of a multi-segmented corridor light showing a first embodiment of a new design; FIG. 2 is a front view for the multi-segmented corridor light shown in FIG. 1;

FIG. 3 is a rear view of the multi-segmented corridor light shown in FIG. 1;

FIG. 4 is a left side view of the multi-segmented corridor light shown in FIG. 1;

FIG. 5 is a right side view of the multi-segmented corridor light shown in FIG. 1;

FIG. 6 is a top side view of the multi-segmented corridor light shown in FIG. 1;

FIG. 7 is a bottom side view of the multi-segmented corridor light shown in FIG. 1;

FIG. 8 is a front perspective view of a multi-segmented corridor light showing a second embodiment of a new design;

FIG. 9 is a front view for the multi-segmented corridor light shown in FIG. 8;

FIG. 10 is a rear view of the multi-segmented corridor light shown in FIG. 8;

FIG. 11 is a left side view of the multi-segmented corridor light shown in FIG. 8;

FIG. 12 is a right side view of the multi-segmented corridor light shown in FIG. 8;

FIG. 13 is a top side view of the multi-segmented corridor light shown in FIG. 8; and,

FIG. 14 is a bottom side view of the multi-segmented corridor light shown in FIG. 8.

The broken lines shown in the drawings represent portions of the multi-segment corridor light in each respective embodiment that form no part of the claimed design.
